UNITED STATES PATENT OFFICE

2,517,503

SANITARY GIRDLE

Alice M. Monjar, Springfield, Ohio

Application January 26, 1948, Serial No. 4,226

2 Claims. (Cl. 2-43)

1

This invention relates to ladies' garments and is concerned primarily with a single garment which is so fabricated that it may be used by the wearer to perform the functions of two or more under garments commonly worn by women.

At the present time many women are desirous of wearing what is known as a panty girdle. Such a garment has all the structural elements of a pair of ladies' panties but is tight fitting and includes panels or sections of an elastic material whereby it is capable of performing the supporting functions of a girdle. Moreover, it has been the practice to anchor the upper ends of garter straps to girdles and similar ladies' garments.

Panty girdles of the type which are now available may ordinarily be worn by the user except for those periods when she requires sanitary protection. The present invention has in view, as its foremost objective, the provision of a garment of the type above indicated which may be worn by the user at all times and which is susceptible, when occasion demands, of having an absorbent pad and a protective insert combined therewith so as to provide the necessary sanitary effects.

In carrying out the above-noted ideas in a practical embodiment it is important that the wearer be enabled to obtain access to her person with a minimum of inconvenience. Thus, a further object is the provision of a garment of the type indicated which includes a seam at a convenient location that is normally closed with a hookless or zipper type slide fastener. With this arrangement the user of one of these garments is enabled to put it on with a minimum of inconvenience and the same may be opened as occasion demands with a minimum of inconvenience.

Another object of the invention is to provide a garment of the type indicated which includes a pair of panels, one being located at each side so as to normally cover the flank of the user and each of these panels is made of an elastic material. This imparts the necessary stretchability to the garment.

A further object of the invention is to provide a garment of the type indicated which includes a crotch section which, in effect, defines the panty construction. This crotch section is made from the same material as the main body portion of the girdle but is ordinarily re-inforced. When occasion demands a protective insert such as one made from rubber or plastic may be detachably secured to the face of this crotch and an absorbent pad anchored to the insert.

2

Various other and more detailed objects and advantages of the invention such as arise in connection with carrying out the above noted ideas in a practical embodiment will in part become apparent and in part be hereinafter stated as the description of the invention proceeds.

The invention, therefore, comprises a ladies' garment which is adapted to function as a pair of panties, a garter belt, a girdle, and a sanitary belt.

For a full and more complete understanding of the invention, reference may be had to the following description and accompanying drawings wherein:

15 Figure 1 is a front view of a garment designed in accordance with the precepts of this invention;

Figure 2 is a back view of the garment shown in Figure 1;

20 Figure 3 is a bottom plan view looking upwardly at the crotch section; and

Figure 4 is a top plan view of the crotch section with the insert attached thereto.

Referring now to the drawing wherein like reference characters denote corresponding parts and first more particularly to Figure 1, the garment of this invention is shown as comprising a front panel 10 designed to cover the abdomen of the wearer and which panel is made from satin or a similar material. A side panel 11 is shown as having one edge secured to the front panel 10 as by the stitching represented at 12. This side panel 11 is made from elastic material. The particular type of elastic material employed is not a part of the present invention as various fabrics of this type are well-known and available on the market as much.

Referring now more particularly to Figure 2, a back panel is represented at 13. The side panel 11 has its other edge anchored to the back panel 13 by the stitching represented at 14. A second side panel 15 which is substantially a duplicate of the side panel 11 has its side edge secured to the other edge of the back panel 13 by the stitching indicated at 16.

Under normal conditions the free edges of the front panel 10 and the side panel 15 will be joined by a hookless or zipper type slide slide fastener represented at 17. It will be understood that this connection at 17 may be opened or closed at the will of the wearer.

A pair of garter straps 18 and 19 have their upper ends secured to the garment in any preferred manner although the invention particularly contemplates that these garter straps or

supporters be removable. Thus, any well-known type of removable connection may be employed in anchoring these straps 18 and 19 in position. Another pair of garter straps or supporters are similarly secured to the other side of the garment and designated 20 and 21.

A crotch section is designated 22 and the front end thereof is defined by the inclined edges 23 and 24 which are stitched to the front panel 10. The rear end of the crotch section 22 is also defined by inclined edges 25 and 26 and these edges are stitched to the rear panel 13.

The garment which has so far been described may be worn by the wearer under normal conditions and will perform the functions of under-panties, a girdle, and garter belt. When occasion arises that the wearer requires sanitary protection an insert shown at 27 is detachably secured to the crotch section 22. The front end of this insert 27 has a formation corresponding to the edges 23 and 24 and it may be detachably secured thereto in any preferred manner such as by the detachable fastening elements shown at 28. Likewise, the edges of the insert 27 correspond in shape to the edges 25 and 26 to which they are secured by the same detachable fastening elements.

The insert 27 is made from a material having good protective qualities such as rubber or synthetic plastic. Pin tabs shown at 29 may be employed for anchoring an absorbent pad to the insert 27. It is notable that the insert 27 at each side extends over and beyond the crotch section 22 so as to afford adequate protection and insure against soilage.

The garment above described may be made in various sizes to suit the body of any particular wearer as a snug fit is highly desirable if not essential to proper functioning of the garment.

While a preferred specific embodiment of the invention is hereinbefore set forth, it is to be clearly understood that the invention is not to be limited to the exact construction illustrated and described, because various modifications of these details may be provided in putting the invention into practice within the purview of the appended claims.

1. A garment of the character described comprising front and back panels of a substantially

non-elastic material, side panels of elastic material with the edges of each side panel being joined to the front and rear panel, respectively, a crotch section joining front and rear panels having concavely curved lateral edges, the edges of such crotch section, the bottom edges of the front and rear panels and the bottom edge of said side panels forming two continuous lower edges defining leg openings, and supporters removably secured to said panels and an insert detachably secured to the opposite ends of said crotch section having edges corresponding in shape and size to said crotch section and fastening means adjacent to the opposite ends of said insert for attaching an absorbent pad thereto.

2. A garment of the character described comprising front and back panels of a substantially non-elastic material, side panels of elastic material with the edges of each side panel being joined to the front and rear panel, respectively, a crotch section joining front and rear panels having concavely curved lateral edges, the edges of such crotch section, the bottom edges of the front and rear panels and the bottom edge of said side panels forming two continuous lower edges defining leg openings, and a protective insert detachably secured to the inner face of said crotch section said crotch section and insert having inclined edges and said insert overlying and covering said crotch section, and means on said insert and at the opposite end thereof for detachably supporting an absorbent pad.
